UNITED STATES PATENT OFFICE.

NORTON A. NEWDICK, OF COLUMBUS, OHIO, ASSIGNOR TO JAMES ELLWOOD JONES, OF SWITCHBACK, WEST VIRGINIA.

LOADING-MACHINE.

1,370,904.

Specification of Letters Patent.

Patented Mar. 8, 1921.

Application filed May 8, 1919. Serial No. 295,609.

To all whom it may concern:

Be it known that I, NORTON A. NEWDICK, a citizen of the United States, residing at Columbus, in the county of Franklin and State of Ohio, have invented certain new and useful Improvements in Loading-Machines, of which the following is a specification.

This invention relates to loading machines adapted to gather and load materials of many kinds but the particular embodiment of the invention herein shown and described being more particularly intended to load coal in the mine into the mine cars.

A primary object of the invention is to provide a single unit loading machine of the character above indicated, constructed in such manner that the discharge end of the gathering conveyer may be maintained in operative position with respect to the mine car, even though the truck of the loading machine and the mine car may be located upon a sharp curve. In machines of this character it is necessary to provide sufficient overhang of the gathering conveyer at the rear of its supporting truck to permit the mine car to be manipulated therebeneath to distribute the load evenly within the mine car. It is apparent that with sufficient overhang to permit the manipulation of a mine car of even moderate length beneath the discharge end of the conveyer, such discharge end will, if the curvature of the track is such as to cause the truck and the mine car to lie at an angle with respect to each other, tend to move laterally beyond the track and consequently beyond the mine car.

The present invention contemplates the provision of a single unit loading machine in which means are provided for permitting the support upon which the gathering conveyer is pivotally supported from its truck, to be shifted bodily laterally to compensate for the tendency of the discharge end of the gathering conveyer to move laterally beyond the mine car under the conditions set forth, whereby such discharge end will be maintained in a position to discharge into the mine car, irrespective of how sharp the curve may be upon which the work is being done.

In the accompanying drawings, which are merely illustrative of the principles constituting the inventive thought,

Figure 1 is a side elevation of a loading machine constructed in accordance with the

invention, with a part of the mounting of 55 the gathering conveyer in section:

And Fig. 2 is a plan view with a part of the gathering conveyer broken away.

Like numerals designate corresponding parts in both of the figures of the drawing. 60

Referring to the drawing, 5 designates the frame of a truck and 6 designates supporting wheels for said truck, these wheels being preferably, though not necessarily, flanged to engage the track upon which the mine car 65 7 travels. At 8 I have diagrammatically illustrated a motor which through pinion 9 and gear 10 is adapted to impart movement to the wheels 6. If desired, sprockets 11 and 12 mounted upon the axles of the truck 70 may be connected by a sprocket chain 13 to cause all of said wheels to be driven from the motor 8. Trunnioned at 14 in the frame of the truck is a saddle casting 15. A rearward extension 16 of this casting is provided with 75 tongues 17 and 18 which enter corresponding grooves 19 and 20 formed in the saddle casting to adapt the rearward extension 16 to have a bodily transverse movement upon the saddle casting 15. In order to impart such 80 bodily movement to the extension 16 said extension is provided with a threaded lug 21 which constitutes a nut and which engages a screw 22. A sprocket 23 upon the end of this screw is connected by a chain 24 with a 85 sprocket 25 upon the shaft of a motor 26. It is apparent that if this motor, which is preferably an electric motor, be energized, rotation will be imparted to the screw 22 and that this will in turn impart bodily lateral 90 movement to the extension 16.

A gathering conveyer 27 is pivotally mounted at 28 in the rear end of the extension 16 and swings about the axis constituted by said pivot so that it may sweep back and forth in a substantially horizontal plane across a mine floor, it being understood that in the drawing this conveyer is merely diagrammatically illustrated, being of a well known type, such, for example, as illustrated 100 in my co-pending application, Serial No. 96,723, filed May 10, 1916.

This type of gathering conveyer comprises a pan 29 divided by a central housing 30 into slideways 31 and 32 in which the flights 105 33 travel, it being understood that these flights are adapted to travel in either direction and that the conveyer is adapted to

gather coal when swung in either direction. The flights 33 are carried by chains indicated at 34 to which motion is imparted from a motor 35. Clips 36 upon the top of the 5 extension 16 engage over an arcuate ring 37 carried by the underside of the pan 29, these clips being disposed upon the arc of a circle struck from the center of the pivot 28. It will thus be seen that as the conveyer swings 10 back and forth it will gather coal or other material and discharge it from the rear end of said conveyer into the mine car 7 and that if the truck of the gathering conveyer and the mine car move to sharply angular positions 15 when working about curves in the mines, the conveyer may be shifted bodily laterally with respect to its supporting truck to keep its discharge end over the mine car.

It is to be noted that the support of the 20 saddle casting is between the axles of the truck so that the weight of the conveyer and of the coal being loaded is equally distributed upon the driving wheels of the truck. Furthermore, this aids in counter-balancing the weight upon the gathering 25 end of the conveyer and relieves friction between the nose of the conveyer and the mine floor.

It is to be understood that the invention 30 is not limited to the precise construction set forth but that it includes within its purview any changes coming within the terms or the spirit of the appended claims.

Having described my invention, what I 35 claim is:

1. In a loading machine, a supporting truck, a saddle casting trunnioned thereon about a horizontal axis, a member slidably mounted upon the saddle casting to move 40 sidewise, means for imparting movement to said member and a gathering conveyer mounted upon said member.

2. In a loading machine, a supporting

truck, a saddle casting trunnioned thereon about a horizontal axis, a member slidably 45 mounted upon the saddle casting to move sidewise, means for imparting movement to said member and a gathering conveyer pivotally mounted upon said member to swing about a vertical axis. 50

3. In a machine of the character described, the combination with a supporting truck, an element trunnioned about a horizontal axis upon said truck, a second element slidably mounted for sidewise movement upon 55 the first named element, and a gathering conveyer pivoted upon the second element.

4. In a loading machine, the combination with a supporting truck, of an element mounted thereon, a second element slidably mounted upon the first named element, a screw carried by one of said elements and engaging the other for imparting sidewise movement to the second element with respect to the first element, means for operating said screw and a gathering conveyer pivoted upon the second element to swing about a vertical axis. 60

5. In a loading machine, the combination with a supporting truck, of an element 70 mounted thereon between the axles of the truck, a rearward extension slidably mounted upon said element to move sidewise, means for imparting movement to said rearward extension and a conveyer supported 75 upon said extension.

6. In a loading machine, the combination with a supporting truck, of an element mounted thereon between the axles of the truck, a rearward extension slidably mounted 80 upon said element to move sidewise, means for imparting movement to said rearward extension and a conveyer pivoted upon said extension to swing about a vertical axis.

In testimony whereof I affix my signature.
NORTON A. NEWDICK.
